INVENTOR

UNITED STATES PATENT OFFICE

HARVEY J. REARDON, OF CHICAGO, ILLINOIS, ASSIGNOR TO THE CLASSROOM TEACHER, INC., OF CHICAGO, ILLINOIS, A CORPORATION OF ILLINOIS

HECTOGRAPH

Application filed May 4, 1932. Serial No. 609,116.

This invention relates to certain novel improvements in hectographs.

This invention relates to that type of devices for manifolding an original which are 5 commonly known as hectographs.

As commonly made these devices comprise a base and a flexible apron adapted to be laid upon the base and bearing a manifolding sheet of gelatin; and it is an object of this invention to provide, in combination with said base and apron, novel, improved, relatively inexpensive, easily operated, and facile means for clamping the apron and the gelatin sheet taut and firmly in manifolding position upon 15 the base.

Fig. 1 is a perspective view of a preferred form of the invention assembled in manifolding position;

Fig. 2 is a perspective fragmentary detail 20 view illustrating my improved apron-clamping means in ineffective or disassembled position; and

Fig. 3 is a sectional detail of the apron-clamping means, taken on line 3—3 in Fig. 1.

25 Referring to the drawing, which illustrates a preferred and practical form of my invention, 10 indicates my improved base or board upon which is laid a conventional flexible apron 11 to one surface of which is adhesively secured, in a manner well known in the art, a 30 manifolding sheet 12 of gelatin.

It is desirable when manifolding from the gelatin sheet 12 that the apron 11 and the 35 gelatin sheet 12 carried thereby be held taut and firmly upon the base 10. It is also desirable that the means for holding or clamping the apron 11 and gelatin sheet 12 upon the base 10 be simple, relatively inexpensive, and easily and facilely operated.

40 To this end and to carry out the hereinbefore stated object of the invention, I provide in each end of the base 10 a groove 13 and I provide a pair of clamping rod members 14 adapted to be received in the grooves 13 to hold the flexible end portions 15 of the 45 apron 11 in said grooves.

To bind the rod members 14 and the apron 50 portions 15 in the grooves 13 I provide a pair of bails or U-shaped clamping members 16, each of which has a slightly yieldable finger

grip portion or handle 18 and parallel arms 17 that are movably or pivotally mounted on the side edge portions of the base 10, by screws 19 or the like.

Each of the clamping rod members 14 is 55 made slightly larger in diameter than the horizontal depth of the grooves 13 so that when said rod members are disposed, with portions 15 of the apron 11, in the grooves 13, a portion 20 (Fig. 3) of each clamping rod 60 member 14 projects outwardly beyond the mouth of the corresponding groove 13, each of which grooves opens at its mouth out onto one of the end edges 21 of the base 10; whereby when the clamping members 16 are swung 65 down into effective position, shown in full lines in Figs. 1 and 3, the slightly yieldable handle or finger grip portions 18 of the clamping members 16 engage the projecting portions 20 of the clamping rod members 14. 70 Said portions 18 are thereby slightly bowed out and bind the clamping rod members 14 against the apron portions 15 and thus bind said apron portions 15 firmly against the edges 22 of the grooves 13; thereby clamping 75 the apron 11 and the gelatin manifolding sheet 12 carried thereby firmly and taut upon the base 10.

The arms 17 of the clamping members 16 when in effective position, as in Fig. 1, close 80 the ends of the grooves 13 and prevent any possibility of axial movement therein of the rod members 14.

To unclamp the apron 11 from the base 10 it is merely necessary to push or lift upwardly on the handle portions 18 of the clamping members 16 and rotate said clamping members upwardly into ineffective position (full lines, Fig. 2, dotted lines Fig. 3) whereupon the clamping rod members 14 and apron portions 15 may be removed from the grooves 13. 90

I claim:

1. A hectograph comprising a base having a groove formed in an end thereof, an apron extended over said base having a manifolding sheet attached thereto and including a flexible end portion receivable in said groove, a rod member receivable in said groove to hold said apron portion therein, and a substantially U-shaped clamping mem- 100

ber including arms pivotally mounted on said base on the sides thereof, said clamping member including a portion extending between said arms adapted in effective position for bearing engagement with said rod member to bind the same and said apron portion in said groove.

2. A hectograph comprising a base having a groove formed in each end thereof, a flexible 10 apron extended over said base having a mani- 70 folding sheet attached thereto and including flexible end portions receivable in said grooves, rod members receivable in said grooves to hold said apron portions therein, 15 and substantially U-shaped clamping members each including a pair of arms pivotally mounted on said base at the sides thereof, each of said U-shaped clamping members including a portion extending between the said 20 arms thereof, said clamping member portions being adapted in effective position to bear against said rod members to bind the latter and said apron portions in said grooves.

3. A hectograph comprising a base having a groove formed in an end thereof, an apron 25 extended over said base having a mani- 75 folding sheet attached thereto and including a flexible end portion receivable in said groove, a rod member receivable in said groove to hold said apron portions therein, and a sub- 80 stantially U-shaped clamping member includ- 85 ing arms pivotally mounted on said base on the sides thereof, said clamping member including a portion extending between said 90 arms adapted in effective position for bearing 95 engagement with said rod member to bind the same and said apron portion in said groove, said clamping member arms in effective position closing the ends of said groove 100 and preventing axial movement of said rod member therein.

4. A hectograph comprising a base having a groove formed in each end thereof, a flexible apron extended over said base having 105 a mani- 110 folding sheet attached thereto and including flexible end portions receivable in said grooves, rod members receivable in said grooves to hold said apron portions therein, and substantially U-shaped clamping mem- 115 bers each including a pair of arms pivotally mounted on said base at the sides thereof, each of said U-shaped clamping members includ- 120 ing a portion extending between the said arms thereof and said clamping member portions being adapted in effective position to bear against said rod members to bind the latter and said apron portions in said grooves, said clamping member arms in effective position closing the ends of said grooves and pre- 125 venting axial movement of said rod members therein.

5. A mani- 130 folding device, comprising a base having a groove formed therein, a mani- 135 folding apron extended over said base hav- 140 ing a portion receivable in said groove, a

rod-like member receivable in said groove to bind said apron portion therein, and a clamp- 70 ing bail having arms pivotally mounted on said base and including a portion extending between said arms adapted to bear against 75 said rod-like member to bind the latter and said apron portion in said groove.

6. A mani- 75 folding device, comprising a base having grooves formed therein, a mani- 80 folding apron extended over said base hav- 85 ing portions receivable in said grooves, rod- 90 like members receivable in said grooves to bind said apron portions therein, and clamp- 95 ing bails each having arms pivotally mounted on said base, each of said bails including a portion extending between the arms thereof, said bail portions being adapted to bear against said rod-like members to bind the latter and said apron portions in said grooves.

In testimony whereof I affix my signature. 85
HARVEY J. REARDON.
